UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A LAVENDER-JAR.

45,542.

Specification for Design.

Patented Mar. 31, 1914.

Application filed December 13, 1913. Serial No. 806,647. Term of patent 14 years.

To all whom it may concern:

Be it known that I, ANDREW J. SANFORD, a citizen of the United States, residing at Newark, in the county of Licking, in the State of Ohio, have invented a new, original, and ornamental Design for Lavender-Jars, of which the following is a specification, reference being had to the accompanying drawing, forming a part thereof.

The figure is a perspective view of a lavender jar showing my new design.

I claim:

The ornamental design for a lavender jar as shown.

ANDREW J. SANFORD.

Witnesses:

J. A. WINTERMUTE,
JOHN MARTIN.
